HEATING FURNACE

Paul S. Menough, Pittsburgh, Pa.

Application November 15, 1933, Serial No. 698,110

14 Claims. (Cl. 263—6)

My invention relates generally to heating furnaces, and more particularly to heating furnaces used for metallurgical purposes and through which the material to be treated is conveyed at such a rate of travel, with reference to the length of the furnace chamber and the heat supplied, as to enable the articles to be properly heated by the time they shall have reached the delivery or discharge end of the furnace. The particular type of heating furnace of this character to which my invention relates is generally known as a "walking beam" type of furnace; that is, a furnace wherein reciprocating members which cooperate with either stationary supports or other reciprocating members are used for transporting the material through the furnace.

Heretofore, considerable difficulty has been experienced in furnaces of this character in providing satisfactory apparatus for transporting material through the furnace, which will not be deleteriously affected by the heat of the furnace. The temperatures in furnaces of this character range up to approximately 1950° F., and sometimes higher, and consequently it is necessary to provide a structure embodying material supporting and moving means which will not be caused to warp or twist when subjected to such temperatures. In order to obviate this difficulty, it has been heretofore proposed to use various alloys for the material supporting and moving apparatus, and particularly those portions of such apparatus which are subjected to the excessive temperatures of the furnace. Alloy materials are, of course, expensive and the use thereof in such furnaces as are known appreciably increase the initial cost of the furnace.

By my invention, I provide a furnace structure of the character above referred to, wherein the amount of alloy required is reduced to a minimum, and the initial cost of which is low as compared with that of other similar satisfactory structures.

In accordance with my invention, I provide a structure wherein the furnace bottom is made up of a plurality of longitudinally extending sections, at least one of which is reciprocable in a longitudinally extending direction. These sections are preferably made of refractory material, and consequently the problem of preventing warping or twisting thereof is completely eliminated. In view of the fact that there is movement of the various sections relative to each other, it is necessary to provide adequate clearance therebetween. If the openings between the various sections are too large or are substantially vertical, I have found that black lines will be formed on the material passing through the furnace immediately above the openings between the sections. Consequently, I further propose by my invention to contour the adjacent faces of the adjacent

sections so as to provide a vertically tortuous passage or slot therebetween.

In accordance with my invention, I further provide novel means carried by the material supporting sections on which the material rests during its passage through the furnace, and which is so arranged as to afford adequate support for the material at all times and prevent bending thereof. The material engaging means which I provide are so arranged as to cooperate with the sections on which they are mounted in such manner as to render it unnecessary to secure them thereon. They are adapted to merely rest on the tops of the sections of the furnace bottom forming the material moving mechanism.

By my invention, I further provide novel means whereby the furnace bottom may be sealed, and whereby any scale and the like which falls through the openings in the furnace bottom may be readily collected and disposed of.

Another feature of my invention resides in the provision of a walking beam type of heating furnace which is adapted to transport tubes or rounds therethrough. Heretofore, it has been deemed impractical to use a walking beam type of furnace for the normalizing of tubes or rounds, in view of the fact that it is necessary to continually or periodically rotate or roll tubes in order to prevent one side from getting an excess amount of heat. Various types of furnaces have been heretofore used in the heating of tubes or rounds, and wherein the tubes or rounds have been rolled or turned either continually or periodically in order to obtain uniform heating. However, walking beam types of furnaces have never been used for this purpose as their use has been deemed impracticable. This turning or rolling of the tubes while they are being heat treated is most essential. If the tubes are not heated uniformly, warping of the tubes will result.

In the furnace which I provide, the tubes or rounds are transported through the furnace by the walking beams and the walking beams are so designed as to cause the tubes to periodically roll thereon in order to turn the tubes and obtain uniform heating or cooling of the tubes. Furthermore, in the structure which I provide, the hot gases may circulate between the walking beams and under the tubes. This also tends toward uniform heating.

Other advantages of my invention will be apparent to those skilled in the art as the nature of my invention is particularly understood. It consists in the novel construction, combination, and arrangement of parts hereinafter more fully described, illustrated and claimed.

In the drawings, I have shown a preferred embodiment of my invention and a modification thereof. It will be understood, however, that I do not intend to be limited to the structures shown

in the drawings, as my invention may be otherwise embodied. In the drawings, my invention is shown as applied to an ordinary "normalizing" furnace. It will be understood, however, that my 5 invention is equally applicable to other types of heating furnaces, for instance, pack heating furnaces.

In the drawings—

Figure 1 is a longitudinal sectional view taken 10 through two different horizontal planes of the furnace which I provide;

Figure 2 is a vertical sectional view of a portion 15 of the furnace shown in Figure 1 taken adjacent and looking toward one of the vertically movable sections;

Figure 3 is a view similar to Figure 2 but taken adjacent and looking toward one of the horizontally movable sections of the furnace;

Figure 4 is a fragmentary elevational view of a 20 portion of the mechanism for moving the horizontally reciprocating sections of the furnace bottom;

Figure 5 is a fragmentary plan view of the vertically and horizontally reciprocable sections of 25 the furnace bottom;

Figure 6 is a fragmentary transverse sectional view showing the reciprocating sections and a portion of the apparatus for moving them;

Figure 7 is a side elevational view of a portion 30 of the apparatus for reciprocating the longitudinally movable sections;

Figure 8 is a transverse section through the furnace shown in Figure 1, the furnace bottom sections being shown more or less diagrammatically;

Figure 9 is a transverse sectional view similar to Figure 6 and showing the furnace which I provide adapted for handling tubes or rounds or the like;

Figure 10 is a fragmentary side elevational view 40 of the material engaging fingers shown in Figure 9 for supporting the tubes or rounds or the like; and

Figure 11 is a side elevational view of material 45 engaging fingers, such as shown in Figure 9, adapted to carry a plurality of tubes tied together by spacing bars.

As shown in the drawings, the furnace structure proper comprises side walls 2, end walls 3, a 50 top wall 4, and a bottom wall indicated generally by the reference character 5. An opening 6 is provided at one end of the furnace to permit material to be placed therein. A discharge opening 7 is provided at the other end of the furnace 55 to permit material to be discharged therefrom after its passage therethrough. The furnace structure may be of any desired width or length depending upon the use to which it is to be put and the size of the materials to be heated.

The material is placed in the furnace and is 60 carried therethrough by means of the reciprocable sections of the furnace bottom. These reciprocable sections may be termed "beams" herein, as they function in a manner similar to the beams 65 of the ordinary type walking beam furnace insofar as the movement of the material through the furnace is concerned. These reciprocable sections, however, are not comparable to the ordinary beams in the usual type of walking beam 70 furnace in any other respects. Their provision is highly desirable and results in a furnace far superior to the types of furnaces now known. The furnace bottom structure or "walking beam" structure for conveying the material through the 75 furnace comprises one series of longitudinally

extending sections 8 which are supported for vertical reciprocatory motion, and a second series of longitudinally extending sections 9 which are supported for horizontal longitudinal reciprocatory movement. The operation of these series of sections or walking beams is so coordinated that the vertically movable sections 8 are in their lowermost position during the period that the longitudinally movable beams are moving forward through the furnace. During this 10 period, the material is supported by the longitudinally movable sections and is carried forward thereby, the vertically movable sections in their lowermost position being below and out of contact with the material. After the forward 15 stroke of the longitudinally movable sections has taken place, the vertically movable sections are raised by appropriate mechanism to be herein-after briefly described, and the material lifted from the longitudinally movable sections 9 and 20 supported thereby. During the period that the material passing through the furnace is supported by the vertically movable sections, the horizontally movable sections are moved rearwardly so as to be ready to receive and again carry forward the material when the vertically movable beams are again lowered. In this manner the material is carried through the furnace in a step-by-step manner, the horizontally movable sections carrying the material forward through the 30 furnace and the vertically movable sections supporting the material during the period that the horizontally movable sections are being returned to a position to again advance the material through the furnace.

It will be understood that my invention is not limited to furnaces having walking beam structures of the character above described, as it may be embodied in structures utilizing an entirely different type of movement. It may be embodied in 40 structures wherein a single series of movable beams or sections are employed, which are movable both in a longitudinally extending direction and a vertically extending direction, the material being supported on stationary supports or sections during the return stroke of the series of 45 movable beams or sections.

Each reciprocable section 8 and 9 is preferably made of refractory material and they are located in close proximity to each other in order to cut down the size of the longitudinally extending slots therebetween to thereby cut down the heat loss and to prevent any influx of cold air into the furnace.

Each longitudinally movable section 9 is carried by angles 10 and secured thereto. Each angle 10 is carried by a longitudinally extending web 11 carried by a trough or tray 12. Angle irons 13 may be provided on either side of the web 11 to give it sufficient rigidity to support the section 9 and the material carried thereby. Each tray or trough 12 extends longitudinally throughout the length of the furnace and is provided with rails 14 adapted to cooperate with wheels 15 carried by a cross shaft 16 supported in bearings 65 in curved bars 17 which are connected together throughout the length of the furnace by spacer bars 18. The wheels 15 are adapted to cooperate with and move along rails 19 formed of channels 70 suitably connected together by means of bolts 20 and spacing sleeves 21. The rails 19 may be suitably mounted on transversely extending pedestals or piers 22.

Extension arms 25 are provided and suitably connected to the longitudinally movable sections 75

9. These extension arms are each provided with a rack 26 adapted to cooperate with a gear 27 carried by a shaft 28 driven by a suitable motor 29 through appropriate gear reducing mechanism 30. Through the mechanism above described, the longitudinally movable sections will be reciprocated longitudinally forwardly and rearwardly through the furnace.

The vertically movable sections 8 are suitably mounted on and secured to angles 35. Each angle is rigidly connected to and supported by a plurality of posts or pins 36. Each post 36 carries a rack 37 adapted to cooperate with a segmental gear 38 driven by a shaft 39 driven by a motor 40 through gear reducing mechanism 41 and other suitable driving connections. These driving connections are shown in the drawings, but it is deemed unnecessary to describe them in detail.

Each vertically reciprocable beam 8 carries a plurality of material engaging fingers 45, and each horizontally reciprocable section or beam 9 carries a plurality of similar material engaging fingers 46. These material engaging fingers are spaced longitudinally of the furnace along the beams or sections 8 or 9 and the material engaging fingers 45 and 46 overlap each other transversely of the furnace but are spaced relative to each other longitudinally of the furnace.

The fingers 46 and the manner in which they are mounted on the beam or section 9 are similar to the fingers 45, and the manner in which they are mounted on the section or beam 8. Consequently, the fingers 45 only will be described.

Each finger 45 is mounted on a substantially V-shaped plate 47 which is adapted to fit over and rest on the substantially V-shaped top portion 48 of the section or beam 8. As shown in the drawings, three of such fingers are tied together adjacent the material engaging surfaces thereof by bars 49. These bars 49 have pointed upper surfaces 50 which are substantially in the same plane as the material engaging surfaces of the fingers and aid in supporting the material.

As will be readily understood from the above description, the material engaging fingers are unsecured to the beams or sections 8 and 9, but nevertheless will remain in position thereon by reason of the manner in which they are mounted thereon. This permits the material engaging surfaces of the transporting mechanism to be readily replaced in the event that they become distorted or disintegrated in any manner by reason of the high temperatures to which they are subjected in the furnace. Furthermore, by reason of the arrangement of the fingers, adequate support is given to the material at all times during its passage through the furnace.

In furnace structures of this character, it is highly desirable to eliminate any substantially straight vertical slots or passageways through the bottom of the furnace. Such substantially straight vertical slots, if allowed to exist, will cause black streaks to form on the material immediately above such slots or passageways. Accordingly, I provide a structure wherein all such substantially straight vertical slots through the bottom of the furnace are eliminated. In accordance with my invention, I provide a structure wherein adjacent faces of adjacent sections provide a tortuous opening. The faces 51 of the vertically reciprocable sections 8 are curved inwardly, as at 52, and the faces 53 of the horizontally reciprocable sections 9 are provided with projections 54 which cooperate with the faces 51

to provide a tortuous passageway or slot through the bottom of the furnace. An arrangement of this character will, as stated above, prevent black streaks from forming on the bottom surfaces of the material immediately above the slots. 5

Furnaces of this character are generally provided with a furnace bottom which is made up of a layer of refractory brick and a layer of heat insulating material therebelow. The heat insulating material is, of course, for the purpose 10 of preventing loss of heat through the furnace bottom. In addition to the provision of a layer of heat insulating material below the refractory material, it is necessary to provide sealing means to seal the furnace against the escape of hot gases 15 or the ingress of cold air around the moving parts extending upwardly through the furnace bottom. In the furnace which I provide, this is accomplished in an entirely novel and considerably less expensive manner. Each base plate 35 on which the sections 8 are mounted is provided with downwardly extending flanges 60. These flanges extend longitudinally of the furnace and are adapted to overlie and extend downwardly into adjacent trays 12, the side walls 61 of each tray being 25 located between the downwardly projecting flanges 60 and the posts 36 carrying the sections 8.

Each tray 12 is provided with heat insulating material 62, such as "silocel", into which the flanges 60 extend for the purpose of effectively 30 sealing the bottom structure of the furnace against the escape of hot gases, or the ingress of cold air or the loss of heat by conduction. As will be readily seen, in a structure such as that which I provide it is unnecessary to provide the 35 furnace bottom with a layer of heat insulating material, as the heat insulating material carried by the trays 12 serves the double purpose of sealing the furnace and preventing heat loss by conduction. 40

Each tray 12 is provided with end walls 62. At least one of the end walls 62 of each tray 12 is removable so as to permit the removal of the trays lengthwise of the furnace. It is highly desirable that these trays be removable as it facilitates the removal of scale and the like which falls therein through the slots in the furnace bottom. It will be readily seen that the furnace bottom structure is of such character as to not retain the scale which drops from the material 50 being carried through, and the scale will drop through the slots in the furnace bottom and into the trays from which it may be removed.

In removing the trays 12 lengthwise of the furnace, the longitudinally reciprocable sections 9 55 will also be removed as the sections or beams 9 are carried by the trays, as described above. This facilitates inspection of the material engaging fingers 46 and the replacement thereof, and also forms a passageway or passageways through the 60 furnace so that a person may enter the furnace and readily examine and replace the material engaging fingers 45 carried by the vertically reciprocable sections 8.

In Figures 9, 10, and 11, I have shown a walking beam furnace structure which is peculiarly applicable to the heating of tubes or rounds or the like. In this embodiment, the material engaging means carried by the vertically movable sections is in the form of a plurality of bars 70 having 70 longitudinally upstanding portions 71. The lower portion of each bar 70 carries forks 72 adapted to rest on the substantially V-shaped portions 73 of the sections 8. By providing a forked bar 70 of this character, the bars may be placed on the 75

- sections 8 without securing or fastening them thereto. The material engaging surfaces 16 of the bars 70 are sloped at an angle to the horizontal toward the discharge end of the furnace.
- 5 The end of each bar 70 closest the discharge end of the furnace is provided with an upwardly extending abutment 74 against which the tubes 75 may rest during a portion of the time they are being transported through the furnace.
- 10 The material engaging means carried by the horizontally movable sections is also in the form of a plurality of bars 70' having longitudinally upstanding portions 71'. The lower portion of each bar 70' carries forks 72' adapted to rest 15 on the substantially V-shaped portion 73' of the beam or section 9. The material engaging surfaces 16' of the bars 70' are substantially horizontal.

In the embodiment shown in the drawings, the stroke of the horizontally movable beams or sections will be of such length as to place the tubes or rounds at the forward end of the stroke in such position as to be engaged by the bars 70 adjacent the rear ends thereof. The tubes will 25 then be caused to roll by gravity along the surfaces thereof until reaching the abutments on the forward ends.

It will be readily understood that the bars 70 may be arranged on both the horizontally and 30 vertically reciprocable sections or beams 8 and 9, and that they may be so positioned that the horizontally movable beams or sections will position the tubes carried thereby on the rear of each bar 70 carried by the vertically reciprocable sections or beams 8, as they are raised to receive 35 the tubes therefrom, and the tubes will roll by gravity along the surfaces thereof until reaching the abutments on the forward ends thereof. Then, as the vertically reciprocable beams or sections 8 are lowered, the horizontally reciprocable beams or sections 9 will have passed through their 40 rearward stroke and will be positioned so that the tubes will be deposited on the bars 70 carried by the longitudinally reciprocable beams or sections 9 adjacent the rear ends thereof, and that 45 the tubes are then rolled along the surfaces of the bars 70 carried by the sections 9 until they reach the abutments 74 at the forward ends thereof.

50 In walking beam furnaces wherein there are a series of horizontally reciprocable beams or sections and a second series of vertically reciprocable beams or sections, the bars 70 or equivalent means may be placed on either series of beams or on both. In furnaces where only one series of movable beams is provided, the bars 70 or equivalent means may be placed on either the stationary supports or the series of reciprocating beams, or 55 on both. Furthermore, in furnaces where only 60 a single reciprocating section or beam is provided, the bars 70 or their equivalents may be placed on either the reciprocable section or the stationary supports, or both.

As shown in Figure 11, a plurality of tubes 80 65 may be tied together by a spacer bar 81 and transported through the furnace together. Where a plurality of such tubes or rounds are tied together and carried through the furnace, they will roll along the inclined material engaging surfaces 73 of the bars 70 forming the material engaging and supporting means.

70 It will be readily seen that a structure such as that shown in Figures 9 to 11, inclusive, is highly desirable for the heating of tubes or rounds, and 75 that the tubes or rounds may be rotated at pre-

determined intervals to prevent warping. A structure of this character permits rapid travel through the furnace without any increase in speed or stroke of the moving mechanism.

In the foregoing specification, I have described 5 my invention as relating generally to heating furnaces, and more particularly to heating furnaces used for metallurgical purposes. My invention is not limited to heating furnaces for metallurgical purposes but relates to heating furnaces of any character whatsoever wherein the material to be treated is conveyed through the furnace at such a rate of travel as to enable the material to be properly heated and treated by the time it reaches the delivery or discharge end 15 of the furnace. It is equally applicable to glass annealing leers, as well as metallurgical furnaces, and the term "heating furnace" as used in the specification and claims hereof includes annealing leers and the like, as well as metallurgical 20 furnaces.

While I have shown and described a preferred embodiment and a modification of one of the features of my invention, it will be understood that I do not intend to be limited thereby, but 25 that the invention may be otherwise embodied within the scope of the appended claims.

I claim:

1. In a continuous heating furnace, a furnace bottom structure comprising a series of spaced 30 longitudinally extending sections formed of refractory material, and a second series of spaced longitudinally extending sections, means for reciprocating one of said series of sections in a longitudinally extending direction through said 35 furnace, the other of said series of sections being adapted to support the material passing through said furnace during the rearward stroke of said reciprocable sections, and a plurality of transversely extending material engaging fingers 40 mounted on at least one of said sections.

2. In a continuous heating furnace, a furnace bottom structure comprising a series of spaced longitudinally extending sections formed of refractory material, and a second series of spaced 45 longitudinally extending sections, means for reciprocating one of said series of sections in a longitudinally extending direction through said furnace, the other of said series of sections being adapted to support the material passing 50 through said furnace during the rearward stroke of said reciprocable sections, and a plurality of transversely extending material engaging fingers resting on and unsecured to at least one of said sections.

3. In a continuous heating furnace, a furnace bottom structure comprising a series of spaced longitudinally extending sections formed of refractory material, and a second series of spaced longitudinally extending sections, means for reciprocating one of said series of sections in a longitudinally extending direction through said furnace, the other of said series of sections being adapted to support the material passing through 60 said furnace during the rearward stroke of said reciprocable sections, and a plurality of spaced transversely extending material engaging fingers mounted on each of said sections and arranged in horizontally overlapping relationship.

4. In a continuous heating furnace, a furnace 70 bottom structure comprising a series of spaced longitudinally extending sections formed of refractory material, and a second series of spaced longitudinally extending sections formed of refractory material and arranged in alternating re- 75

- lationship relative to said first series of sections, means for reciprocating said first series of sections in a vertically extending direction, and means for reciprocating said second series of sections in a longitudinally extending direction, and a plurality of spaced transversely extending material engaging fingers mounted on each of said sections.
5. In a continuous heating furnace, means for moving material through the furnace comprising a series of spaced longitudinally extending beams, means for reciprocating said beams in a longitudinally extending direction, a plurality of transversely extending material engaging and supporting fingers carried by at least one of said beams, said fingers being spaced longitudinally of the furnace, and means arranged between said spaced beams for supporting the material during the return stroke of said beams.
10. 6. In a continuous heating furnace, means for moving material through the furnace comprising a series of spaced longitudinally extending beams, means for reciprocating said beams in a longitudinally extending direction, a plurality of transversely extending material engaging and supporting fingers carried by at least one of said beams, said fingers being spaced longitudinally of the furnace, and means arranged between said spaced beams for supporting the material during the return stroke of said beams, and a plurality of transversely extending material engaging and supporting fingers carried by at least one of said beams, said fingers being spaced longitudinally of the furnace, and being arranged in alternating relationship relative to the material supporting fingers carried by said beams.
15. 7. In a continuous heating furnace, a furnace bottom structure comprising a series of spaced longitudinally extending sections formed of refractory material, the adjacent faces of said sections being arranged to provide a vertically tortuous slot between adjacent sections.
20. 8. In a continuous heating furnace, a furnace bottom structure comprising a series of spaced longitudinally extending sections formed of refractory material, and a second series of spaced longitudinally extending sections, and means for reciprocating one of said series of sections in a longitudinally extending direction through said furnace, the other of said series of sections being adapted to support the material passing through the furnace during the rearward stroke of said reciprocable sections, adjacent faces of adjacent sections being arranged to provide a vertically tortuous slot therebetween.
25. 9. In a continuous heating furnace, a furnace bottom structure comprising a series of spaced longitudinally extending sections formed of refractory material, and a second series of spaced longitudinally extending sections formed of refractory material and arranged in alternating relationship relative to said first series of sections, means for reciprocating said first series of sections in a vertically extending direction, and means for reciprocating said second series of sections in a longitudinally extending direction, adjacent faces of adjacent sections being arranged to provide a vertically tortuous slot therebetween.
30. 10. In a continuous heating furnace, a furnace bottom structure comprising a plurality of longitudinally extending supports, means for reciprocating at least one of said supports in a longitudinally extending direction, a tray positioned below said reciprocating support containing heat insulating material, and means depending downwardly from one of said supports and adapted to extend into said heat insulating material, whereby the furnace bottom is sealed against the exit of hot gases or ingress of cold air around said reciprocatory section.
35. 11. In a continuous heating furnace, a furnace bottom structure comprising a plurality of longitudinally extending supports, means for reciprocating at least one of said supports in a longitudinally extending direction, at least one of said remaining supports being adapted to support the material during at least a part of one stroke of said reciprocating support, a tray positioned below said reciprocating support containing heat insulating material, and means depending downwardly from one of said supports and adapted to extend into said heat insulating material, whereby the furnace bottom is sealed against the exit of hot gases or ingress of cold air around said reciprocatory section and against heat loss through the furnace bottom.
40. 12. In a continuous heating furnace, a furnace bottom structure comprising a series of spaced longitudinally extending sections, and a second series of spaced longitudinally extending sections, means for reciprocating one of said series of sections in a longitudinally extending direction through said furnace, the other of said series of sections being adapted to support the material passing through the furnace during the rearward stroke of said reciprocable sections, and a plurality of trays having therein heat insulating material positioned below said longitudinally reciprocable sections, the other of said series of sections having downwardly depending longitudinally extending flanges adapted to extend into said heat insulating material, whereby the furnace bottom is sealed against heat loss by convection or conduction.
45. 13. In a continuous heating furnace, means for moving material through the furnace comprising a series of longitudinally extending supports, means for reciprocating said series of supports in a longitudinally extending direction, a second series of supports arranged in alternating relationship relative to said first mentioned series of supports, and adapted to support the material during at least a part of one stroke of said reciprocating supports, each of one series of supports having downwardly extending flanges thereon, and longitudinally extending trays positioned below the other series of supports adapted to cooperate with said flanges to seal the furnace.
50. 14. In a continuous heating furnace, a furnace bottom structure comprising a series of spaced longitudinally extending sections formed of refractory material, and a second series of spaced longitudinally extending sections, means for reciprocating one of said series of sections in a longitudinally extending direction through said furnace, the other of said series of sections being adapted to support the material passing through the furnace during the rearward stroke of said reciprocable sections, and means for supporting each of said longitudinally reciprocable sections including a tray positioned therebelow.

PAUL S. MENOUGH.
